LOCK

Frederick W. Heyel, Port Chester, N. Y., assignor
to Kemp Lock, Inc., New York, N. Y., a corpora-
tion of New York

Application April 14, 1934, Serial No. 720,543

12 Claims. (Cl. 70—29)

This invention relates to locks.

An object of this invention is to provide an improved door lock adapted to be opened or closed from the inside by a knob or from the outside by a key, and adapted to be set for dead bolting to prevent opening of the lock from the inside by the knob after the lock has been closed by the key from the outside.

A further object of this invention is to provide a lock of the character described, constructed to release or render inoperative the setting means each time the lock is opened either by the key or by the knob. Thus, should a person leave the premises by a door provided with my improved lock, the person may open the lock from the inside by turning the knob, then set the lock, leave the premises, shut the door and lock the lock with a key. Thereafter, the lock cannot be opened from the inside of the premises by the knob, for example, by a thief entering the premises through the window.

A still further object of this invention is to provide a strong, compact and durable lock of the character described, which shall comprise comparatively few and simple parts, be relatively inexpensive to manufacture, smooth and positive in operation, and withal practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible embodiments of my invention,

Fig. 1 is an elevational interior view of a lock embodying the invention, in unlocked condition, with the rear cover plate broken away and parts in cross-section;

Fig. 2 is a cross-sectional view taken on line 2—2 of Fig. 1;

Fig. 3 is a view similar to Fig. 1, but illustrating the lock in locked condition, the lock not being set for dead bolting;

Fig. 4 is a partial view similar to Fig. 1, but showing the lock set for dead bolting, and illustrating the position of the parts partially moved toward closing position;

Fig. 5 is a view similar to Fig. 4, but showing the lock in fully locked position;

Fig. 6 is a cross-sectional view taken on line 6—6 of Fig. 1;

Fig. 7 is a cross-sectional view taken on line 7—7 of Fig. 1;

Fig. 8 is a perspective view of one of the vertical bolts; and

Fig. 9 is a perspective view of the setting mechanism.

Referring now in detail to the drawings, 10 designates a lock embodying the invention, comprising a casing 11 attached to the edge of a door 12, and a keeper 13 attached to the door jamb 14. The casing 11 is provided with top, bottom and end walls, and is open at the rear, said rear being enclosed by a rear cover plate 17. 15 The end wall 18 adjacent the edge of the door is provided with an opening 19 slidably receiving the horizontal bolt 20. The top and bottom walls of the casing are formed with aligned hollow portions 21 of square cross-section in which there 20 are mounted a pair of vertical bolts 22. Each of the bolts 22 is provided with a portion 23 which slides in the hollow portion 21 and has an axial through opening and a U-shaped portion 24 provided with a stem 25 journaled in said opening 25 and having at the inner end thereof a pinion 26.

The rear cover plate 17 is provided with a pair of fixed, inwardly extending pins 28. A pair of pivoted plates 29, lying substantially against the interior surface of the cover plate 17, are formed 30 with openings pivotally receiving the pins 28, and have openings 30 at the outer ends thereof, receiving pins 31 on the portions 23 of the vertical bolts 22.

The horizontal bolt 20 is provided with a pair of 35 raked portions 33 adapted to coat with the pinions 26 on the stems 25 of the bolt portions 23. Said horizontal bolt 20 is further provided with a pair of rearward extensions 35 and 36 in which there is slidably mounted for movement in a direction perpendicular to the direction of movement of said horizontal bolt, a slider 37. Fixed to said slider 37 is a tubular member 40. A knob 41 rotatably mounted on the front of the casing 11, is provided with an arm 42 having at the outer end thereof, a pin 43 received within the tubular member 40.

The pivot plates 29 are formed with slots 46 receiving pins 47 fixed to the horizontal bolt. The slots 46 are so shaped that upon turning the knob 50 to lock the lock, the horizontal bolt is projected to the right, and during the projecting movement thereof, the vertical bolts are first moved away from each other, and the portions 24 of said vertical bolts are then rotated 180°, due to the 55

interengagement of the rack portions 33 with the pinions 26. The vertical bolts are then moved inwardly toward each other to engage the keeper 13. The operation of the knob 41, the horizontal bolt 20, the vertical bolts 22 and the pivot plates 5 29 is described in detail in the patent of Charles Kemp and Irving Kemp, No. 1,937,897, patented December 5, 1933.

Means is provided to lock the lock by means of 10 a key. To this end a sleeve 50 is journaled in a bearing formed on the rear cover plate 17. Fixed to said sleeve is a plate 51 provided with a relatively short pin 52 and a relatively long pin 53. The tube 40 is formed with a semi-cylindrical portion 54 adapted to receive the longer pin 53. The short pin 52, however, cannot contact said semi-circular portion 54. A usual cylinder lock 57 may be mounted on the door 12 actuated by a key 58 and provided with the usual connecting bar 59 projecting through a slot 60 in the sleeve 59. Upon turning the key 58, the bar 59 turns the sleeve 50 and the plate 51.

It will now be understood that when the key is turned in a counter-clockwise direction, looking 25 at Fig. 1 of the drawings, the pin 53 engaging the semi-circular portion 54, will cause the slider 37 to project the horizontal bolt fully upon turning the key 180°. Upon continuing to turn the key through another 180°, the pin 53 will merely 30 lift out of the semi-circular portion 54, to permit free rotation of the plate 51 without affecting the bolts. To unlock the lock by means of the key, the key is merely turned in a clockwise direction through first 180° without affecting the bolts to 35 bring the pin 53 into the semi-circular portion 54 and through another 180° during which the slider 37 will move from the position shown in Fig. 3, to the position shown in Fig. 1, for retracting the horizontal bolt.

40 The lock is furthermore provided with setting mechanism 64 shown in detail in Fig. 9 of the drawings, which when set, will prevent the lock from being opened by the knob 41 after locking the lock by the key 58. To this end, there is rotatably mounted on the tubular member 40 a member 45 65 having a projecting finger 66 and being formed with a ledge 67 extending at right angles to the plane of said finger. The pin 52 on plate 51 can contact ledge 67 but not finger 66. There is 50 furthermore fixed to the cover plate 17 a pin 70 for the purpose hereinafter appearing. The pin 70 is so positioned that every time the lock is unlocked, the finger 66 will strike said pin and be moved to the position shown in Fig. 1 of the 55 drawings, if the position of finger 66 has been relatively changed by striking unit 64. In said position, the pin 52 on the plate 51 will not contact either the finger 66 or the ledge 67 upon locking the lock with the key. Fig. 3 shows the 60 pin 52 as being located on the left of the ledge 67. Thus normally, neither the finger 66 nor the ledge 67 affects the operation of the lock.

The setting mechanism 64 comprises a plate 65 75 slidably mounted on the bottom wall of the lock casing. Extending upwardly from the plate 75 is a vertical wall 76. The plate 75 is formed with a slot 77 adjacent the wall 76, and with a pair of aligned slots 78. Said plate 75 is furthermore formed with a notch or groove 79 adjacent one end thereof and adjacent the wall 76. Extending from the plate 75 is an extension 80 from which there extends upwardly a wall 81 provided with a finger 82 disposed at right angles 70 to the plate 75 and wall 76. Pivoted to the plate 75

76 is a bell crank lever 84 having an arm 85 projecting through the slot 77, and an arm 86 substantially parallel to the wall 76 and having a foot 88 extending upwardly at the outer end thereof.

5 The arm 86 is formed with a slot 90 receiving one end of a strip spring 91, the lower end of 10 which extends within the notch 79 and contacts the bottom wall of the casing. The arm 85 projects through a slot 93 in the bottom wall of 15 the lock casing. Said slot 93 is longer than slot 77, permitting a limited pivotal movement of lever 84. It will now be understood that the spring 91 normally tends to rotate the bell crank 15 the drawings. Movement of the bell crank, however, is limited by the ends of the slot 77.

20 Fixed to the bottom wall of the casing are a pair of pins 95 projecting through the slots 78 and having heads 96 contacting the top surface 20 of the plate 75. It will now be understood that the setting mechanism may be moved to the right or to the left by engaging the downwardly projecting portion of the arm 85.

25 In Fig. 1 of the drawings, the setting mechanism is shown in inoperative or released position, having been moved to the extreme left, and the arm 85 substantially contacting the left end of 30 the slot 93. When the setting mechanism is in released position, the finger 82 is so positioned that the finger 66 will not contact the same, when the lock is locked or unlocked either by the 35 knob 41 or the key 58. However, should a person leaving the premises unlock the lock by the 40 knob from the inside and then move the arm 85 to the right from the position shown in Fig. 1 to the position shown in Fig. 4, the setting mechanism 45 64 will be in operative position. Upon the person thereafter leaving the premises, shutting the door, and locking the lock with the key, the finger 66 will contact the finger 82 as the 50 horizontal bolt is projected, and be moved to substantially horizontal position as shown in Fig. 5 of the drawings. As shown in Fig. 5, the pin 52 will then be located beneath the ledge 67 and contact the same. Thereafter, the lock cannot be unlocked by the knob, for example, by a 55 thief entering the premises through a window. This is due to the engagement of the ledge 67 with the pin 52. Looking at Fig. 5, movement of the arm 42 fixed to the knob 41 in a clockwise direction is prevented, since the ledge 67 contacts the pin 52 on the plate 51, which cannot move. The lock may thus be unlocked only by 60 the key 58.

65 With the parts as shown in Fig. 5 of the drawings, unlocking of the lock with the key will also cause the bottom corner 100 of the horizontal bolt 20 to engage the foot 88 of the bell crank 84 and slide the setting mechanism bodily to the left, or inoperative position. In fact, whenever the lock is unlocked either by the key or by the knob, the horizontal bolt will engage the bell crank and move the setting mechanism to releasing or inoperative position. The setting mechanism is thus prevented from being in operative position except when it is set prior to leaving the premises. The likelihood of the setting mechanism being in operative position when 70 it is not desired, is thus minimized.

75 It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter here-
in set forth or shown in the accompanying drawings is to be interpreted as illustrative and not in a limiting sense, except as set forth in the claims.

Having thus described my invention, I claim as
10 new and desire to secure by Letters Patent:

1. In a lock, a bolt, knob actuated means for locking and unlocking the lock, key actuated means for locking or unlocking the lock, means for preventing unlocking of the lock by the knob after the lock has been locked by the key, and means for rendering the last mentioned means inoperative so as to permit the lock to be unlocked by the knob after the lock has been locked by the key.

2. A lock comprising a casing, a knob rotatably mounted on said casing, means actuated by said knob for locking or unlocking the lock, key actuated mechanism for locking or unlocking said lock, mechanism within said casing adapted in one position thereof to prevent unlocking of the lock by the knob actuated mechanism after locking the lock by the key actuated mechanism, and in another position thereof, to permit locking and unlocking of the lock by either the knob actuated mechanism or the key actuated mechanism.

3. A lock comprising a casing, a knob rotatably mounted on said casing, means actuated by said knob for locking or unlocking the lock, key actuated mechanism for locking or unlocking said lock, mechanism within said casing adapted in one position thereof to prevent unlocking of the lock by the knob actuated mechanism after locking the lock by the key actuated mechanism, and in another position thereof, to permit locking and unlocking of the lock by either the knob-actuated mechanism or the key actuated mechanism, and means for moving said mechanism to the latter position thereof each time the lock is unlocked.

4. A lock comprising a casing, a bolt slidably mounted therein, means for slidably moving said bolt comprising a knob rotatably mounted on said casing, an arm fixed to said knob, a plate slidably mounted on said bolt for movement in a direction transverse to the direction of movement of said bolt, a tubular member mounted on said plate, a pin on said arm received within said tubular member, said tubular member having a semi-circular portion, said casing having a rear cover, a plate rotatably mounted on said rear cover, key actuated means for rotating said last mentioned plate, a pin on said last mentioned plate adapted to be received within said semi-circular portion, a member on said tubular member having a finger and a ledge, a pin on said cover adapted to engage said finger upon retracting said bolt for rotating said last member in one direction, means within said casing adapted to engage said finger to cause rotation of the last member in the opposite direction upon projecting said bolt, and a second pin on said last mentioned plate adapted to contact said ledge after said last member has been moved by said means when the bolt is projected to prevent retraction of said bolt without rotation of said plate by said key actuated mechanism to move said second pin away from said ledge, and said means comprising a member adapted to be engaged by said bolt and moved to said position by said bolt each time the bolt is retracted.

5. In a lock, a bolt, knob actuated means for locking and unlocking the lock, key actuated means for locking or unlocking the lock, means for preventing unlocking of the lock by the knob after the lock has been locked by the key, means for rendering the last mentioned means inoperative, said last means comprising a member slidably mounted on said casing, said casing having a slot, and means on said member extending through said slot.

6. A lock comprising a casing, a bolt slidably mounted therein a knob rotatably mounted on said casing, an arm fixed to said knob within said casing and having a pin thereon, a rear cover for said casing, a plate mounted on said cover for rotation about the axis of said knob and having a pin thereon, key actuated means for rotating said plate, a member operatively

connected to said bolt and provided with a tubular member receiving the pin on said arm, and having a semi-cylindrical portion adapted to receive the pin on said plate, said bolt being adapted to be projected and retracted by said knob or key actuated mechanism, a member rotatably mounted on said tubular member and having a finger, and a ledge extending beyond the plane of said finger, a pin on said rear cover adapted to engage said finger for rotating said last member in one direction to one angular position upon reTRACTING said bolt, a second pin on said plate out of contact with said ledge during retraction or projection of said bolt when said last member is in said angular position, and means within said casing for moving said last member in an opposite direction to another angular position upon projecting said bolt by said key actuated mechanism, and said second pin being adapted to engage said ledge in said other angular position of said last member to prevent retraction of said bolt by said knob.

9. A lock comprising a casing, a bolt slidably mounted therein, a knob rotatably mounted on said casing, an arm fixed to said knob within said casing and having a pin thereon, a rear cover for said casing, a plate mounted on said cover for rotation about the axis of said knob and having a pin thereon, key actuated means for rotating said plate, a member operatively connected to said bolt and provided with a tubular member receiving the pin on said arm, and having a semi-cylindrical portion adapted to receive the pin on said plate, said bolt being adapted to be projected and retracted by said knob or key actuated mechanism, a member rotatably mounted on said tubular member and having a finger, and a ledge extending beyond the plane of said finger, a pin on said rear cover adapted to engage said finger for rotating said last member in one direction to one angular position upon reTRACTING said bolt, a second pin on said plate out of contact with said ledge during retraction or projection of said bolt when said last member is in said angular position, and means within said casing for moving said last member in an opposite direction to another angular position upon projecting said bolt by said key actuated mechanism, and said second pin being adapted to engage said ledge in said other angular position of said last member to prevent retraction of said bolt by said knob.

10. A lock comprising a casing, a bolt slidably mounted therein, a knob rotatably mounted on said casing, an arm fixed to said knob within said casing and having a pin thereon, a rear cover for said casing, a plate mounted on said cover for rotation about the axis of said knob and having a pin thereon, key actuated means for rotating said plate, a member operatively connected to said bolt and provided with a tubular member receiving the pin on said arm, and having a semi-cylindrical portion adapted to receive the pin on said plate, said bolt being adapted to be projected and retracted by said knob or key actuated mechanism, a member rotatably mounted on said tubular member and having a finger, and a ledge extending beyond the plane of said finger, a pin on said rear cover adapted to engage said finger for rotating said last member in one direction to one angular position upon reTRACTING said bolt, a second pin on said plate out of contact with said ledge during retraction or projection of said bolt when said last member is in said angular position, and means within said casing for moving said last member in an opposite direction to another angular position upon projecting said bolt by said key actuated mechanism, and said second pin being adapted to engage said ledge in said other angular position of said last member to prevent retraction of said bolt by said knob.

11. In a lock, a bolt, knob-actuated means for locking and unlocking the lock, key actuated means for locking or unlocking the lock, means for preventing unlocking of the lock by the knob after the lock has been locked by the key, and means for rendering the last mentioned means inoperative so as to permit the lock to be unlocked by the knob after the lock has been locked by the key, said rendering means being actuatable from the exterior of said casing.

12. A lock comprising a casing, a knob rotatably mounted on said casing, means actuated by said knob for locking or unlocking the lock, key actuated mechanism for locking or unlocking said lock, mechanism within said casing adapted in one position thereof to prevent unlocking of the lock by the knob actuated mechanism after locking the lock by the key actuated mechanism, and in another position thereof, to permit locking and unlocking of the lock by either the knob actuated mechanism or the key actuated mechanism, and means projecting from said casing for controlling the position of said mechanism.

said bolt and provided with a tubular member receiving the pin on said arm, and having a semi-cylindrical portion adapted to receive the pin on said plate, said bolt being adapted to be projected and retracted by said knob or key actuated mechanism, a member rotatably mounted on said tubular member and having a finger, and a ledge extending beyond the plane of said finger, a pin on said rear cover adapted to engage said finger for rotating said last member in one direction to one angular position upon reTRACTING said bolt, a second pin on said plate out of contact with said ledge during retraction or projection of said bolt when said last member is in said angular position, and means within said casing for moving said last member in an opposite direction to another angular position upon projecting said bolt by said key actuated mechanism, and said second pin being adapted to engage said ledge in said other angular position of said last member to prevent retraction of said bolt by said knob, said means comprising a member slidably mounted on a wall of said casing and being movable to inoperative position where the same will not engage said finger or rotate said member in said opposite direction to said other angular position thereof upon projecting said bolt by said key actuated mechanism, said slidably mounted member being formed with a slot, said wall being formed with a slot registering with but longer than the slot in said slidably mounted member, a bell crank lever pivoted on said slidably mounted member and having a finger projecting through said registering slots to the exterior of said casing, spring means for causing limited pivotal movement of said bell crank in one direction, said bell crank having a foot, and said bolt having a portion adapted to engage said foot for causing sliding movement of said slidably mounted member to inoperative position each time the bolt is retracted.

13. In a lock, a bolt, knob-actuated means for locking and unlocking the lock, key actuated means for locking or unlocking the lock, means for preventing unlocking of the lock by the knob after the lock has been locked by the key, and means for rendering the last mentioned means inoperative so as to permit the lock to be unlocked by the knob after the lock has been locked by the key, said rendering means being actuatable from the exterior of said casing.

14. A lock comprising a casing, a knob rotatably mounted on said casing, means actuated by said knob for locking or unlocking the lock, key actuated mechanism for locking or unlocking said lock, mechanism within said casing adapted in one position thereof to prevent unlocking of the lock by the knob actuated mechanism after locking the lock by the key actuated mechanism, and in another position thereof, to permit locking and unlocking of the lock by either the knob actuated mechanism or the key actuated mechanism, and means projecting from said casing for controlling the position of said mechanism.

FREDERICK W. HEYEL.
